UNITED STATES PATENT OFFICE.

HELLMUTH LEHMKUHL, OF ST. PAUL, MINNESOTA.

STENCILING APPARATUS.

1,168,655.

Specification of Letters Patent.

Patented Jan. 18, 1916.

Application filed November 30, 1914. Serial No. 874,894.

To all whom it may concern:

Be it known that I, HELLMUTH LEHMKUHL, a subject of Germany, residing at St. Paul, in the county of Ramsey and State of Minnesota, have invented a new and useful Improvement in Stenciling Apparatus, of which the following is a specification.

The primary object of this invention is the production of a stenciling apparatus, which is adapted to facilitate the selection of a stencil of required size, and causing it to register accurately with the material to be printed upon, so that signs, store announcements and the like can be easily and accurately prepared.

A further object is the production of simple and inexpensive construction.

These and other objects will be apparent from the following description, in which the accompanying drawing forms part thereof.

Figure 1 is a plan of my invention; Fig. 2 is a side view of a detail, and Fig. 3 is a plan of the head piece on an enlarged scale, part of the structure being broken away.

In the drawing, A indicates a portable base of any suitable dimensions and material, having two oppositely disposed vertical supports B of similar construction at its upper end and disposed at each side. Each of these supports consists of a bearing bracket in the form of a plate secured to the side edges of the base by screws C or other suitable means. A portion of this plate projecting above the surface of the base is formed with a vertical slot D and a lateral channel E, extending forwardly and forming an opening in extension of said slot for receiving a gudgeon such as F into the slot. Disposed horizontally between the supports B and across the upper end of the surface of the base is a head piece G in the form of a block made of wood or other suitable material having polygonal sides H of any suitable number, the drawing illustrating three, and a cross section of the block being substantially a triangle with the apexes cut off to produce straight shoulders Q. The ends of the block are provided with gudgeons F in the form of stud bolts threaded on their outer ends and projecting from the ends of the head block on its axis. These gudgeons are adapted to be passed into the slots D of the supports B through the channels E, where the

block is rotatably supported and free to be lifted, while remaining in the supports, so that the block can be turned and any one of its sides made to rest upon the surface of the base. Along each longitudinal edge 60 of the block, a scale such as J is graduated, the graduations of all of the scales being different for the purpose of designating the stencil such as K, which should be used with the head piece, there being a stencil or set 65 of stencils provided for coöperation with each scale. The stencils of each set or group are marked for identification so that they can be selected for use with a corresponding scale on the head piece. In Fig. 1 the 70 scale which is in position for use is marked by the numeral 3 at a point substantially midway between the ends of the block and the stencil has a similar identification mark near its right hand end. This mode of 75 marking the scales and stencils is carried out on all of the scales and stencils, different identification marks being employed.

In use the material such as a sheet of paper L is placed upon the base in desired 80 position, and the head piece made to rest upon the material, the head piece serving as a weight to hold the material in position. Thumb nuts M on the threaded ends of the gudgeons are then screwed down against the 85 supports B, thus clamping the head piece firmly upon its supports, while the material L is held in position on the surface of the base. The stencil can then be adjusted along the longitudinal straight shoulders Q of the 90 head piece, and the material stenciled. The shoulders Q of the head piece form guiding straight edges along which the stencil can readily be selectively positioned. The scales on the head piece are graduated from 95 a center line N to enable the material being centered on the base. The surface of the base is also provided with scales O, the graduations being numbered or marked from a point P, indicating a line bi-secting 100 the base vertically to assist in enabling the user positioning the material such as L centrally upon the base. The base is also graduated with line spaces P', which are numbered for convenience in selecting a 105 stencil having letters of desired height or size for use. The operation of the apparatus is extremely simple, as well as its construction, the material being easily adjusted upon the surface of the base, where it is held by 110

the head piece in position, so that a stencil of desired size can be selected and employed for preparing a sign of any character.

The scales J are graduated along the opposite edges of each side of the head piece, their order being reversed so that by changing the head piece end for end two scales are provided on each side, making double the number of different scales in all available upon the head piece.

In accordance with the patent statutes, I have described the principles of operation of my invention, together with the apparatus which I now consider to represent the best embodiment thereof, but I desire to have it understood that the construction shown is only illustrative, and that the invention can be carried out by other means and applied to uses other than those above set forth within the scope of the following claims.

Having described my invention, what I claim as new and desire to protect by Letters Patent is:—

1. In a stenciling apparatus, the combination with a base for supporting material to be stenciled, of a head piece formed with a plurality of substantially flat sides having scales graduated thereon for assisting in positioning the material to be stenciled laterally upon the surface of said base, and supports on said base, in which said head piece is rotatable and movable up and down, whereby said head piece is adapted to be rigidly secured with either of its sides resting down upon and holding said material secured flat upon the base, said head having a series of straight edges against any one of which a stencil may be arranged for po-

sitioning the same longitudinally of said base.

2. In a stenciling apparatus, the combination with a base for supporting material to be stenciled, of a head piece formed with a plurality of substantially flat sides having graduated scales along the longitudinal edges of one of its sides for assisting in positioning the material to be stenciled on the surface of said base, and supports on said base in which said head piece is changeably supported end for end and freely movable up and down, whereby said head piece can be positioned with any of its scales on a side facing downwardly along the surface of said base and with its weight resting and holding the material positioned upon said base.

3. In a stenciling apparatus, the combination with a base for supporting material to be stenciled, of a head piece formed with a plurality of substantially flat sides having scales graduated along the longitudinal edges of each of its sides for assisting in positioning the material to be stenciled laterally upon the surface of said base, and supports on said base in which said head piece is rotatable and changeably supported end for end, whereby said head piece can be reversed and rotated with any of its scales facing downwardly along the surface of said base, for the purposes specified.

In testimony whereof, I have signed my name to this specification, in the presence of two subscribing witnesses.

HELLMUTH LEHMKUHL.
